UNITED STATES PATENT OFFICE.

CHARLES G. KLEIN, OF ELMIRA, NEW YORK.

PLUMBER'S TEST APPARATUS.

1,159,847.

Specification of Letters Patent.

Patented Nov. 9, 1915.

Application filed May 11, 1915. Serial No. 27,414.

To all whom it may concern:

Be it known that I, CHARLES G. KLEIN, a citizen of the United States, and resident of Elmira, county of Chemung, State of New York, have invented certain new and useful Improvements in Plumbers' Test Apparatus, of which the following is a specification.

My invention relates to plumbers' test apparatus and more particularly to a device for use in discovering leaks in plumbing waste pipes, by means of forcing smoke, essence of peppermint or other suitable detector into the pipes.

15 The object of the invention is to provide a simple portable device for the above purpose which can be easily connected to the plumbing to be tested and which can be easily manipulated to ascertain whether the plumbing leaks.

20 The above and other objects and the novel features of the invention will be apparent from the following description taken in connection with the drawing which is a central 25 vertical sectional view of an apparatus embodying my invention.

Referring to the drawing the device comprises a cylindrical sheet metal casing or tank 10 provided with beads at its upper 30 and lower end to stiffen it and having the flat bottom 11, which closes the tank at the bottom. The upper end of the tank has a bail 12 secured thereto by the ears 13 so as to provide a handle for the device by means 35 of which it may be conveniently carried from place to place.

The tank or casing 10 is divided intermediate its ends into two compartments by a partition 14. The partition 14 has a flange 15 at its peripheral edge by means of 40 which it rests on and is secured to an interior circumferential bead 16 located a slight distance above the bottom 11 in the casing 10. The partition 14 has an upwardly tapering part 17 at the inner edge of the flange 15, and the upper end of the tapering part 17 is joined to a horizontal portion 18.

As above stated, the partition 14 divides 45 the casing 10 horizontally into two compartments, the lower compartment located be-

tween the partition and the bottom 11 constituting the smoke generating chamber 19 and being adapted to receive a charge of material such as waste or the like to produce 55 the smoke used in the operation of the device. The smoke generating chamber 19 has an inlet opening 20 in the side wall of the same through which the material may be charged into the chamber 19. The opening 60 20 also serves as an inlet for supplying the necessary air for the combustion of the gas or smoke producing material.

The water chamber 21 is located above the gas generating chamber 19 and has a 65 filling inlet at 22 joined to a vertically extending pipe 23 on the outside of the tank 10. The pipe 23 at its lower end has a connection 24 which extends into the smoke generating chamber 19 and has an upwardly 70 extending limb 25 passing through the horizontal part 18 of the partition between the chambers. A pipe nipple 26 is fitted in the upper open end of the pipe 23 and when the tank is filled with water the nipple 26 75 is removed, the water level being determined by the height of the pipe 23. Therefore, when the water overflows at the inlet to the pipe 23 the proper water level will have been reached. While the device is in use the nipple 26 is screwed in place.

The vertically extending pipe 25 passes through the partition 18 and extends upwardly a considerable distance above the normal water level in the chamber 21. The 85 pipe 25 has a smoke inlet 27 at its extreme upper end and also has a series of smoke and water outlets 28 located at the normal water level in the tank 21. The end surrounding the inlet 27 is secured to the top 29 of an 90 inclosing wall 30 which is mounted and secured to the partition member 18. The walls 29 and 30 inclose a compartment 31 which receives the smoke issuing from the outlets 28 in the pipe 25. The smoke in the 95 compartment 31 discharges through an outlet pipe consisting of the vertical part 32 and the horizontal part 33. The vertical part 32 has an inlet 34 near the top of the compartment 31, and the pipe 32 extends 100 down through the partition wall 18 into the smoke chamber 19 and is joined to the sec-

tion 33 which extends laterally through the side wall of the chamber 19 and is provided at its outside end with a coupling member 35 whereby it may be attached by some suitable means to the plumbing to be tested.

5 The smoke chamber 19 is connected to the water chamber 21 by means of a curved pipe 36 which is mounted on the partition wall 18, extends upwardly and is bent so that its 10 outlet end 37 terminates below the normal water level in the tank 21, thereby providing a water seal between the chambers 19 and 21.

A bell 38 having a cylindrical wall 39 and 15 a top wall 40 is fitted in the tank 10, the cylindrical wall 39 being of such size that its open end extends into the tapering portion of the water chamber 21 provided by the tapering wall 17. Normally the bell rests 20 on the flange 15 at the bottom of the water chamber, and it may be lifted by means of a handle 42 fastened on the top 40 of the bell. The bell provides the gas chamber 43 above the water level and surrounding the 25 pipe 36 and gas compartment 31.

The operation of the device is briefly as follows:—The smoke producing material having been introduced into the gas generating chamber 19 and ignited, an upward 30 pull on the bell causes a vacuum or decrease of pressure in the gas compartment 43 and draws smoke into that compartment through the duct 36. The water in discharge pipe 27 is drawn upward by this vacuum sealing the 35 series of outlets 28 at the water level, because the pipe 25 being open at its extreme upper end, when the vacuum is created within the compartment 43, the greater atmospheric pressure acts on the water in 23 and 40 25 to raise the level in the compartment 43. The gas outlets 28 are closed when the level of the water rises, consequently the gas in the pipe 32 and the chamber 30 will not return into the chamber 43 formed by the 45 bell, as a partial vacuum is created in the chamber 43 when the bell is lifted to draw in gas from the generating chamber. By thus preventing communication between the chamber 43 and the outlet 34, a pumping 50 55 back and forth of the gas is prevented. By releasing the bell the weight thereof will exert pressure on the gas to force the same through the outlets 27 and 28 and into the inlet 34 of the discharge pipe 32, 33 from which it enters the plumbing and the leakage of the latter may thereby be ascertained. Of course, additional pressure may be applied to the bell by pushing it downwardly. The bell may also be graduated so as to indicate 60 the extent of the leakage. The depth of the tank 21 into which the edge of the wall 39 extends may be varied so as to give the bell a greater or lesser movement, as it is desired.

While I have shown and described my 65 invention in detail I do not wish to be limited to the exact construction disclosed as it is obvious that various modifications may be made therein without departing from the spirit of the invention.

Having thus described my invention what 70 I claim is:—

1. In a device of the class described, the combination of a water chamber, a gas generating chamber, a duct leading from the 75 gas generating chamber to the water chamber and terminating below the water level in the latter, said water chamber having a gas outlet, and means for drawing gas through said duct into the water chamber 80 and for forcing gas out of the water chamber through said outlet, communication between said outlet and the water chamber being prevented when gas is drawn into the water chamber by said means.

2. In a device of the class described, the combination of a tank having a partition dividing the tank into a water chamber and a chamber to receive a charge of material for producing a gas, said charge receiving chamber having an inlet for air, a duct leading from said charge receiving chamber to said water chamber and terminating below the water level in the latter, said water chamber having a gas outlet, and 90 means for drawing gas through said duct into the water chamber and capable of forcing the gas out of the water chamber through said outlet, the latter being closed 95 when gas is drawn into the water chamber 100 by said means.

3. In a device of the class described, the combination of a water chamber, a gas generating chamber, a duct leading from said gas generating chamber to said water chamber and terminating below the water level in the latter, said water chamber having a gas outlet approximately at the water level in said water chamber, and a bell in the water chamber providing a gas receiving 105 compartment above the water level, said bell being adapted to be raised to draw gas from the generating chamber through said duct into said compartment and capable of exerting pressure on the gas in the compartment to force it through the outlet in the water chamber, the gas outlet at the water level being adapted to be closed by the water which rises in said water chamber when the bell is raised to create a lower pressure to 110 draw in gas from said generating chamber.

4. In a device of the class described, the combination of a tank having a partition dividing the tank horizontally into a water chamber and a chamber below the water 115 chamber to receive a charge of material for producing a gas, said charge receiving chamber having an inlet for air, a duct

- leading from the top of the charge receiving chamber to the water chamber and terminating below the water level in the latter, said water chamber having a gas outlet through 5 its bottom, and a bell in the water chamber having its lower end extending below the level of the water and providing a gas compartment above the water level, said bell being movable so as to draw gas from 10 the gas generating chamber through said duct into the gas compartment in the bell, and being also capable of exerting a pressure on the gas in said compartment to force it out through the gas outlet of the water 15 chamber, communication between said gas outlet and the water chamber being prevented when said bell is raised.
5. In a device of the class described the combination of a water chamber, a filling 20 connection for said chamber, a gas generating chamber having an inlet for air, and for charging material into said generating chamber, a duct leading from said gas generating chamber to said water chamber and terminating below the water level in the latter, the outlet in the water chamber of said filling connection being located above the end of said duct, said water chamber having a gas outlet, and means for drawing 25 gas through said duct into the water chamber and capable of forcing the gas from the chamber through said outlet therein, communication between said gas outlet and filling connection being prevented by the rise 30 of the water in said water chamber when said gas drawing and forcing means is operated to draw in gas.
6. In a device of the class described, the combination of a water chamber, a bell in 35 the water chamber forming a gas compartment above the water level in the latter, a filling pipe extending into the bell having an outlet at the water level in the water chamber, a gas generating chamber, 40 a duct leading from the gas generating chamber to the water chamber and terminating within the bell and beneath the water level therein, a gas outlet duct having its inlet above the water level in the bell, said bell being movable so as to withdraw gas from the gas generating chamber into the bell and capable of exerting pressure thereon to force the gas out through 45 the outlet duct.
- 55 7. In a device of the class described, the combination of a water chamber, a filling pipe extending into the water chamber above the level of the water therein and having an outlet at the water level, a gas 60 compartment surrounding said filling pipe and connected thereto at the top, said filling pipe being open at its upper end, a gas outlet duct extending from above the water level in said gas compartment out of the water chamber, and means for exerting 65 pressure on gas in said water chamber to force the gas into the upper end of the filling pipe whereby the gas will flow out of the filling pipe through the outlet at the water level and into the inlet of the gas 70 outlet duct.
8. In a device of the class described the combination of a water chamber, a filling 75 pipe extending into the water chamber, said filling pipe having outlets at the water level and having a gas inlet located above the water level, a gas duct having an inlet above the water level and leading out of the water chamber, a wall inclosing the inlet of the gas outlet duct and the outlets of the water filling pipe, a gas generating chamber, a duct leading from said gas generating chamber and terminating below the water level in 80 said water chamber, and a bell in the water chamber capable of drawing gas from said generating chamber into the bell and exerting pressure thereon whereby the gas is forced into the upper end of the filling pipe, out through the openings therein and into the gas outlet duct. 90
9. In a device of the class described the combination of a portable casing or tank, a handle for the same, a partition above the bottom of the casing providing a smoke generating chamber between the bottom of the 95 casing and said partition, said smoke generating chamber having an opening serving as an inlet for air and for charging material into said generating chamber, the space in said chamber above said partition serving as a 100 water chamber, a filling connection for maintaining the water at a predetermined level above said partition, a duct establishing communication between said smoke generating chamber and the water chamber and terminating below the water level in the latter, a smoke outlet pipe having its inlet located above the water level in the water chamber and extending through the smoke chamber, and a bell in the water chamber 110 surrounding the smoke inlet duct and the smoke outlet pipe, said bell having a handle whereby it may be raised so as to create a vacuum above the water level in the water chamber to draw smoke into the bell from said smoke generating chamber, said bell being capable of exerting pressure on the smoke therein to force the smoke out through the outlet pipe. 115
10. In a device of the class described, the 120 combination of a gas generating chamber, a water chamber having a portion at its edge surrounding the upper end of said generating chamber, a bell having its open end fitting in said portion of the water chamber, a duct leading from said generating chamber and terminating below the water level in said bell, a gas discharge pipe having its 125

inlet located inside said bell above the water level therein, and leading outside said water chamber, and means whereby communication between said gas discharge pipe and the space within the bell is prevented by the rise of the water in said water chamber when said bell is operated to draw in gas.

In testimony whereof I affix my signature in presence of two witnesses.
